US00D964482S

(12) **United States Design Patent** (10) Patent No.: **US D964,482 S**
(45) Date of Patent: ** *Sep. 20, 2022

(54) **MODEL VEHICLE PLATFORM**(71) Applicant: **TRAXXAS LP**, McKinney, TX (US)(72) Inventors: **Adam Cole Ewing**, McKinney, TX (US); **Jory Sprowl**, Honey Grove, TX (US); **Terry Soward**, Van Alstyne, TX (US); **Jaime Felix Barajas**, Dallas, TX (US); **Casey Christen Jens Christensen**, McKinney, TX (US); **Jonathan Scott Wood**, Frisco, TX (US); **Skylar Hagler**, Anna, TX (US); **Otto Karl Allmendinger**, Rowlett, TX (US); **Kent Poteet**, Lucas, TX (US)(73) Assignee: **TRAXXAS LP**, McKinney, TX (US)

(*) Notice: This patent is subject to a terminal disclaimer.

(**) Term: **15 Years**(21) Appl. No.: **29/688,166**(22) Filed: **Apr. 18, 2019**(51) LOC (13) Cl. **21-01**

CLAIM

We claim the ornamental design for a model vehicle platform, as shown and described.

DESCRIPTION

FIG. 1 is an upper, left, front perspective view of a model vehicle platform;

FIG. 2 is front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a lower, right, rear perspective view thereof.

In the drawings, the broken line showing of features of a model vehicle platform illustrate portions of the model vehicle platform that form no part of the claimed design.
